UNITED STATES PATENT OFFICE.

JAMES SKATSCHKOFF, OF ST. PETERSBURG, RUSSIA.

MEANS FOR RAISING SUNKEN VESSELS.

994,611.

Specification of Letters Patent. Patented June 6, 1911.

Application filed December 17, 1909. Serial No. 533,682.

To all whom it may concern:

Be it known that I, JAMES SKATSCHKOFF, a subject of the Emperor of Russia, and a resident of 1 Degtarnoipereoulok, St. Petersburg, Russia, practical engineer, have invented a new and useful Means for Raising Sunken Vessels, of which the following is a specification.

In the accompanying drawings Figure 1 is a plan view of the case employed for inclosing the upper portion of a vessel to be raised. Fig. 2 is a side view of the same. Fig. 3 is a partly diagrammatic side view, with portions broken away, of a sunken vessel having the apparatus for raising it applied thereto as in practice.

In carrying out the invention, a case or casing is made of waterproof tarpaulin which is open at the bottom, the plan view 20 of the case resembling the form of the vessel which is to be raised. The case thus consists of a top portion and side walls, which latter extend down far enough to inclose the upper portion of the hull of the vessel.

In order to raise a sunken vessel the usual practice is to apply the hoisting power of air bags, barrels and other arrangements, by suspending the vessel which it is intended to raise to them, or the vessel is raised by 30 means of a floating crane. In both cases the vessel represents dead weight which it is necessary to raise. In the proposed means of raising of sunken vessels, this latter does not form a dead weight, but becomes a self-35 raising apparatus in view of which fact the water filling it is discharged and replaced with air.

On cutting down the masts and high chimneys, the case is let down with the aid 40 of divers upon the vessel and the sides of this latter are grasped by the walls of the case which are fastened in some way to the sides of the vessel. For this purpose, for instance, several rows of steel ropes *e*, *e*, *e*, 45 furnished with tightening devices, are fastened to the lower edge of the case. When the case has been placed upon the vessel and the ropes have been tightened, the whole arrangement will have the appearance 50 shown in Fig. 3. Two series of pipes for

air delivery *b*, *b* and water suction *a*, *a*, pass through the cover of the case (as at *c*, *c*, *d*, *d*); the ends of the latter must be let down near the bottom of the vessel and the former can end at the very cover. After the case 55 has been placed upon the vessel and made fast on the same, they form a closed space filled with water, which has to be forced out and replaced with air in order that the vessel may obtain buoyancy. This is attained by the delivery of air through pipes *b*, *b* and in the case of necessity by pumping out the water through pipes *a*, *a*, keeping up the pressure of the air in accordance with the depth at which the vessel has sunk. 60 When the water inside the vessel has been replaced with air it obtains immense hoisting power, while the dead weight is reduced by an amount equal to the weight of all the water which filled it and the vessel 65 floats up. When the vessel is being raised the exterior pressure will become less and therefore, automatic safety-valves must be installed in the case, in order to balance it with the interior pressure. Under these 70 conditions the material of the case hardly undergoes any tension and therefore the danger of its tearing apart is done away with. It is of course understood that the calculation for determining the strength of 75 all the parts must be made specially for each separate case.

What I claim as my invention and desire to secure by Letters Patent is:

1. For raising sunken vessels, the apparatus hereinbefore described, the same comprising an air- and water-proof case having pendent sides and a closed top and the general form of the vessel which is to be raised, whereby it is adapted to be applied over the 85 upper portion of the vessel, means for securing such case to the hull of the vessel, and pipes attached to the case and serving to remove water and admit air, substantially as described. 90

2. In an apparatus for raising sunken vessels, an air- and water-proof case formed of flexible material and made of a size and shape corresponding to the vessel over whose upper portion it is to be applied, 100

ropes having fastening devices and adapted to be passed around the vessel lengthwise thereof and over the lower edge of the case for clamping the case tightly to the hull, and water and air pipes forming an attachment of the upper portion of the case, as shown and described.

In testimony whereof, I have signed my name to this specification in the presence of two subscribing witnesses.

JAMES SKATSCHKOFF.

Witnesses:

H. A. LOVIAGUINE,
A. TSCHERALOFF.
